HARRY S. VINCENT, OF RIDGEWOOD, NEW JERSEY, ASSIGNOR TO FRANKLIN RAILWAY SUPPLY COMPANY, OF NEW YORK, N. Y., A CORPORATION OF DELAWARE

STEAM ENGINE

Application filed August 6, 1927. Serial No. 211,051.

This invention relates to steam engines and more particularly to valve mechanism therefor.

A primary object of the invention is to make conveniently possible, especially with a poppet-type valve, an early cut-off of steam without loss of power in starting and at slow speeds. With this object in view the invention is particularly useful in locomotives and will be hereinafter shown and described as applied to a locomotive valve similar to the Lentz poppet type.

More specifically my invention contemplates the attainment, in a poppet valve with its advantage of quick movement to full open and closed positions, of early cut-off of the main portion of the steam supply, along with an extended cut-off of a limited portion thereof which in starting and at slow speeds gives the effect of a late cut-off.

Another object of the invention is to provide mechanism to attain the foregoing advantages, which shall be positive in operation, simple in construction, and readily applicable to existing poppet-valve equipment.

How I attain the foregoing, together with such other objects and advantages as are incident to my invention or will occur to those skilled in the art, will appear from the following description taken together with the accompanying drawings, in which:

Figure 1 illustrates in longitudinal vertical section the upper portion of a cylinder and a steam chest mounted thereon, the latter having positioned therein the valve mechanism embodying the present invention, with certain cam parts exaggerated in their proportions for purposes of illustration; and

Figure 2 is an enlarged view of the cam mechanism shown in Fig. 1, indicating the true proportions of the cam and the operation thereof.

It will be understood that the mechanism shown is for admission of the steam to the cylinder 2, the exhaust valves being in a separate chamber of the chest 3, to one side of the admission valves, and exhausting through outlets indicated at 4, 4, but the exhaust valve mechanism is not shown since

it forms no part of the present invention. At 2b and 3b I have indicated a cylinder lubrication pipe and a cam chamber drain.

As shown in Fig. 1, steam is admitted to the chamber 5 of the chest 3 through inlet 6. 55 Near the ends of the chamber are annular valve members 7, 8, one for each end of the cylinder, each valve having edges or flanges 9, 10, adapted to seat, respectively on the annular valve seats 11, 12. These ring-like 60 valves 7, 8, are supported, as by webs 13 and collars 14, on reciprocable rods or shafts 15 and 16, respectively, and held as against endwise movement on said rods by shoulders 17, and rings and lock nuts 18 and 19. 65 Since the diameter of the flange 9, of each valve, is greater than the diameter of its flange 10, the steam pressure in chamber 5 will tend to hold the valve in seated position, the position shown at the right of 70 Figure 1. The steam, having access also to the spring chambers 20, 20, will act on the outer ends of valve-stems 15, 16, tending further to hold the valves in closed position. To insure the proper closing of the 75 valve, particularly when the steam is off, a spring 21 is inserted in each chamber 20, such spring bearing on the outer side of ring 18, the compression thereof being adjustable by means of a screw 22 and lock-nut 23.

When a valve is open the steam passes between the flange 9 and seat 11, and between the flange 10 and seat 12, into the passage 24 and from thence into the end of the cylinder through admission port 25. The opening and closing of the valves is controlled by the oscillating cam 26, which is secured on the transverse shaft 27, as by keys 28. The shaft is rotated back and forth by any suitable crank or arm (not shown) connected to the usual valve motion mechanism of the locomotive. The valve rods or stems 15, 16, bear, through the intermediation of rollers 29, 30, on the outer surface or periphery of 85 the stepped cam member 26, and are movable longitudinally in bushings 31. When the portion 32 of the cam's surface (which is farthest from its axis) engages either roller, 90 the respective rod is forced outwards and 100

the valve is opened wide giving free admission of the steam to the respective cylinder end. At such time the roller of the opposite valve will be adjacent the portion 33 of the cam's surface (which is nearest its axis) and the corresponding valve will be closed. Assuming, now, that the piston 2a in cylinder 2 is at the left end and is about to move to the right, and that the valve motion of the locomotive is set to give a cut-off of 50%. The roller 29 will be bearing on the portion 32 of the surface of the cam and valve 7 will be wide open. When the piston has moved to the center of its stroke, i. e. 15 50%, the cam will have been turned to the right until the roller is in engagement with the intermediate cam surface 34a. This is the point of normal cut-off at running speeds, but it will be seen that the valve 7 20 is still cracked open, and for starting, or slow running, steam will enter the cylinder through the crack and build up a pressure sufficient to move the locomotive. During 25 this period the roller 30 is on the portion 33 of the cam's surface, and valve 8 remains closed. As the piston moves farther to the right, the cam will turn until, for example at 75% of stroke, the roller 29 is on the portion 33 of the cam's surface and valve 7 30 will be seated. Upon further movement roller 30 of valve 8 will bear on surface 34b of the cam, opening the valve slightly, which will cause preadmission of steam to the right hand end of the cylinder which escapes 35 through the right hand exhaust valve (not shown) while said exhaust valve is open, and cushions the piston when such exhaust valve closes. As the cam moves farther to the right, roller 30 will engage portion 32 40 of the cam's surface and valve 8 will be open wide, at which time the piston is at the right hand end of cylinder 2 and ready for the return stroke to the left. The entire operation is then reversed, main cut-off for the right 45 hand end occurring when roller 30 engages surface 34b, at which time the piston, in the example given, has travelled half way to the left, and complete closure of valve 8 occurring when the roller 30 again rides on portion 50 33 of the cam's surface. It will thus be seen that a stepped or interrupted movement of the valve mechanism, corresponding to the steps of the actuating cam, is obtained.

55 The foregoing operation of the valves with regard to the movement of the cam will be particularly clear from inspection of Fig. 2.

60 For clarity of illustration only, the cam surfaces or steps 34a and 34b are exaggerated in Fig. 1, the crack at valve 7 being shown correspondingly greater than it is in actual practice. Fig. 2 shows surfaces 34a 65 and 34b only slightly higher than surface

33, the actual difference, in practice, being about .01 of an inch.

The operation, in brief, will now be seen to be such that at high speeds the effective cut-off occurs when the rollers 29, 30 engage the respective cam surfaces 34a, 34b, while at starting and when the engine is running at slow speeds the slight opening at the valves, caused by the cam surfaces 34a and 34b, will be sufficient to provide the necessary power, providing, in effect, an extended cut-off up to any desired percentage of the stroke, for example 75 or 80 per cent. 75

80 It will thus be seen that by my improvement, a short limited cut-off may be used with a poppet admission valve, while at the same time obtaining, in effect, a long cut-off for starting and slow-speed running; also that the device is simple, positive in operation, and inexpensive to construct; and 85 that the improved cam construction may be readily applied to existing poppet or other forms of valve equipment.

What I claim is:—

1. In valve mechanism of the character 90 described, a poppet valve, a stem therefor, and an oscillatory actuating cam engaging the stem, said cam having its engaging surface constructed with three stepped portions at respectively different distances from the 95 cam axis, one of which portions holds the valve in full open position during a portion of the cam's oscillation, the next of which portions holds the valve partially open during the next succeeding portion of the cam's 100 oscillation, and the third of which portions permits complete closure of the valve during the next succeeding portion of the cam's oscillation.

2. In poppet valve steam admission mechanism of the character described, a valve, a seat therefor, and a cam having a stepped surface with a portion adapted to hold said valve from its seat, an adjacent portion adapted to permit only a partial movement 105 of the valve toward its seat, and a portion adjacent said second-mentioned portion adapted to permit seating of the valve.

3. In limited cut-off steam engine mechanism of the character described having cylinder and piston, valve means, and a triple-stepped actuating means therefor constructed to control said valve means by stepped movements, said stepped actuating means including means adapted to produce a momentarily substantially fixed valve opening of relatively small area during partial movement of the piston, whereby to provide an extension of the cut-off which is substantially ineffective at high speeds of the engine. 115 120

4. In an engine having a cylinder and piston, steam admission mechanism including a valve and a co-operating port, and a valve-actuating device having stepped valve- 130

- controlling means including means adapted to hold said valve in open position, means adapted to permit only a partial movement of the valve toward closure of said port, 5 means for holding the valve at an intermediate constant opening during partial movement of the piston, and means adapted to permit movement of the valve to fully close said port.
- 10 5. In a steam engine having a cylinder and piston, a valve, a movable cam device for actuating said valve, said cam device including means for holding said valve in open position during a portion of the piston 15 stroke and cam movement, means stepped from said first-mentioned means for holding said valve open at a constant lift during a further portion of the piston stroke and cam movement, and means stepped from said 20 second-mentioned means for fully closing said valve during a still further portion of the piston stroke and cam movement.

In testimony whereof I have hereunto signed my name.
